CLAIM

The ornamental design for a footwear oversized sneaker and sole, as shown and described.

DESCRIPTION

FIG. 1 is a perspective view of a footwear oversized sneaker and sole showing my new design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The broken lines in the drawings showing the laces, the tabs on either side of the uppermost lace, and the long rectangle on the sole shown in FIG. 7, form no part of the claimed design. Otherwise, the broken lines in the drawings illustrate stitching and form no part of the claimed design.
